„No Model.“

D. B. SOPER.

CHURN.

Patented Sept. 28, 1886.

No. 349,759.

UNITED STATES PATENT OFFICE.

DWIGHT B. SOPER, OF FLINT, MICHIGAN.

CHURN.

SPECIFICATION forming part of Letters Patent No. 349,759, dated September 28, 1886.

Application filed June 19, 1886. Serial No. 204,717. (No model.)

To all whom it may concern:

Be it known that I, DWIGHT B. SOPER, a citizen of the United States, residing at Flint, in the county of Genesee and State of Michigan, have invented certain new and useful Improvements in Churns, of which the following is a full, clear, and exact description.

This invention relates to that class of churns in which the body containing the fluid is rotated upon a fixed axis in order to produce butter.

The invention consists in a cover for such and similar churns, and in details of construction, all as hereinafter more particularly set forth and claimed.

In the accompanying drawings, in the several figures of which like parts are similarly designated, Figure 1 is a side elevation. Fig. 2 is a top view. Fig. 3 is a cross-section of the top of the body in the line of the length of the clamping-arms. Fig. 4 is a similar section at right angles to the last-named section. Fig. 5 is a detail of the clamping-arm, holding-plates, or socket; and Fig. 6 is a perspective 25 of part of the cover-receiving head or rim and one of the catches for the clamping-arms.

A suitable platform, *a*, from which rise parallel vertical posts *b*, is prepared to receive the churn-body *c*, which last is here shown as a cask or barrel, and it may be of any approved construction and size or sizes and material. The churn-body in this instance is shown provided with gudgeons or journals *d d*, suitably affixed to opposite sides of the body about midway of its length and in the same horizontal plane, and resting and turning in bearings in the tops of the posts *b*. On one of these journals is secured a pinion, *e*, which meshes with an internally-toothed driving-wheel, *f*, the latter being secured to a journal, *g*, made fast to one of the posts *b*, and also provided with a crank or handle, *h*, for rotating said wheel by hand, though, obviously, a band-wheel may be connected to the said driving-wheel for connecting the churn with means for driving it by power, using ordinary means and power to this end. The gear-wheels *e f*, I prefer to be in the proportion of about one to three, so as to get increased motion at a small expenditure of power.

The churn-body may be held stationary to the post at an incline for emptying it of spent

liquor through an outlet, *i*, by a hook and eye, *j*.

The details so far described may be varied 55 at pleasure without departing from the spirit and essence of my invention.

The chief feature of my invention I will now proceed to set forth.

The bottom of the churn-body may be of the 60 construction commonly employed in heading barrels.

The fixed part of the cover is composed of a metallic annular rim, *k*, flat on the under side and beveled on the upper side, so as to fit into 65 the chine, the same as an ordinary barrel-head, and secured therein by the hoops, as usual in heading barrels. This rim is provided with an internal rabbeted lip, *l*. The removable cover *m*, of wood by preference, is provided on its 70 under side with a rabbet, *n*, in which is fitted a packing, *o*, of cork or other material or substance of a like yielding or conforming quality. This packed edge of the cover engages the rabbeted lip of the annular rim, so as to 75 make a tight joint therewith. The edge of the cover is bound by an angle-plate, *p*, which projects over and keeps the packing *o* in place, besides strengthening and preserving the edge of such cover. In the center of the cover is 80 arranged a metallic internally screw-threaded socket, *q*, into which is fitted a screw-post, *r*, having the shoulder *r'*, and rising above the latter, the diametrically-reduced round journal *r''*, which is continued as a squared portion, *r''*, 85 and terminates in the screw-threaded portion *r''*. A plate, *s*, rests upon the shoulder *r'* of the screw-post *r*, and this plate has a diametric socket, *s'*, which receives the ends of the cover-clamping arms *t*, which, when in 90 place in the said socketed plate, are retained therein by a plate, *s''*, having the socket *s'*, to match and cover the socketed plate *s*. The plates *s* and *s''*, with the arms *t* in place therein, are held together, and the post *r* rotated so 95 as to raise and lower it in the screw-socket *q*, by means of a handle, *u*, secured to the squared portion *r''* of the post by a nut, *u'*, on the portion *r''*, it being obvious that rotating the handle will rotate the screw-post, and hence raise 100 and lower it in its socket, and consequently raise and lower the arms *t t*. These arms *t t* extend diametrically across the cover and work in guides *v*, rising from the angle-plate *p*, and

extend slightly beyond the cover. They are held to place in the said guides by loops *w*, secured to the plate *p*, and their outer ends are constructed to engage right and left catches *x*, 5 fast on the annular rim *k* and rising from the top thereof. It will be understood that by raising the post *r*, the arms *t* are loosened from the catches, and by then giving the cover a partial rotation the said arms escape sidewise 10 from the catches and the cover may be removed. By replacing the cover and inserting the arms again in the catches, and then rotating the screw-post, so as to lower it into its socket *q*, the arms are forced home into the 15 catches, and the guide *v*, acting as fulcrum for said arms, the continued downward movement of the screw-post will cause the arms to act as levers with the catches as the weight, and hence bind the cover tightly to its seat in 20 the rim *k*. The action of the parts *r*, *s*, *s'*, and *u* upon the arms *t* is practically that of an eccentric.

A glazed opening, *y*, may be made in the cover to inspect the interior of the body, and 25 hence note the progress of the churning. Obviously this closure may be applied to vessels generally, and hence my invention is not limited to churns.

What I claim is—

1. A body, *e*, provided with an annular rab- 30 beted rim secured in the chine like a barrel-head, a cover provided with a packed edge to fit in said annular rim, and cover-clamping arms arranged upon said cover and engaging catches on the said rim, combined with a 35 screw-threaded socket in said cover, a rotary threaded post arranged in said socket, socket-plates on said post receiving the said clamp- 40 ing-arms, and a device to rotate said post, substantially as described.

2. The cover provided with a screw-threaded socket, combined with a rotary threaded post, *r*, arms *t*, socket-plates *s* *s'* on said post receiving the said arms, and an operating-han- 45 dle for said post, substantially as described.

3. The cover, a screw-threaded socket there- 50 in, a rotary threaded post in said socket, socket-plates on said post, arms seated in said plates, and an operating-handle for said post, combined with guides for said arms, a rim, and catches on said rim with which said arms are engaged, substantially as described.

In testimony whereof I have hereunto set my hand this 7th day of June, A. D. 1886.

DWIGHT B. SOPER.
